CLAIM

The ornamental design for a tactical laser with picatinny rail, as shown and described.

DESCRIPTION

FIG. 1 is a front, right and top perspective view of a tactical laser with picatinny rail showing my new design;

FIG. 2 is a rear, left and bottom perspective view thereof;

FIG. 3 is a top plan view thereof;

FIG. 4 is a bottom plan view thereof;

FIG. 5 is a left view thereof;

FIG. 6 is a right view thereof;

FIG. 7 is a rear elevational view thereof; and

FIG. 8 is a front elevational view thereof.
